UNITED STATES PATENT OFFICE.

JOHN B. HADAWAY, OF BROCKTON, MASSACHUSETTS, ASSIGNOR TO THE GEM FLEXIBLE INSOLE COMPANY, OF BOSTON, MASSACHUSETTS.

DESIGN FOR A CEMENT-RECEPTACLE.

SPECIFICATION forming part of Design No. 28,547, dated May 3, 1898.

Application filed January 4, 1898. Serial No. 665,586. Term of patent 14 years.

To all whom it may concern:

Be it known that I, JOHN B. HADAWAY, a citizen of the United States, residing at Brockton, in the county of Plymouth and State of Massachusetts, have invented and produced a new and original Design for Cement-Receptacles, of which the following is a specification, reference being had to the accompanying drawings, forming a part of this application.

Figure 1 is a top plan view of a cement-receptacle embodying my design. Fig. 2 is a reversed plan view. Fig. 3 is a side elevation, and Figs. 4 and 5 are the respective end elevations of the cement-receptacle.

As shown in the drawings, the main or body portion A of the cement-receptacle is in plan view substantially elliptical in shape and its upper and lower edges a and a' are rounded, as clearly shown in Figs. 3, 4, and 5 of the drawings. Upon the top or upper surface a² of the body portion A are formed the upwardly-extending projections a³ and a⁴, said projections being substantially circular in outline and the projection a⁴ being somewhat larger in circumference than the projection a³. The projection a³ is covered by a cap a⁵, which is provided with a knob or handle a⁶, which is substantially circular in plan. The projection a⁴ is extended laterally, as shown at a⁷, and such projections a⁷ are provided with the inwardly-extending vertical slots a⁸. The projection a⁴ is covered by a cap a⁹, said cap being substantially circular in plan view, and at each side is provided with the lateral extensions a¹⁰, provided with

the notches a¹¹, as clearly shown in Fig. 1. The cap a⁹ also is provided with vertical uprights a¹², located adjacent to the projections a¹⁰.

The base of the receptacle within the lines bounded by the curved edge a' and at one end of the body portion A is provided with a substantially circular portion A', which portion is laterally extended at its base, forming a flange a¹³, which flange at diametrically opposite sides is extended, as shown at a¹⁴, which extensions are provided with the notches a¹⁵. The base at the opposite end of the body portion A has a downwardly-extending standard or foot a¹⁶, tapering, as shown, and radiating from three sides of said foot a¹⁶ are the curved braces a¹⁷, the brace at the forward portion merging into a flange a¹⁸. (Clearly shown in Fig. 3.) The standard or foot a¹⁶ and the circular portion a' are united by a brace a¹⁹, which is formed with the upwardly curved or arched portion a²⁰, the flange a¹⁸ and a¹³ being united by a flange a²¹, extending beneath the brace a¹⁹. The main body portion A is shown as being perfectly plain.

I claim—

The design for a cement-receptacle, substantially as shown and described.

In testimony whereof I affix my signature in presence of two witnesses.

JOHN B. HADAWAY.
